J. A. L. DETERS.

AUTOMATIC CUT-OUT FOR GAS BURNERS.
APPLICATION FILED JUNE 29, 1917.

Patented May 28, 1918.

UNITED STATES PATENT OFFICE.

JOHN A. L. DETERS, OF CHICAGO, ILLINOIS.

AUTOMATIC CUT-OUT FOR GAS-BURNERS.

1,267,519.

Specification of Letters Patent. Patented May 28, 1918.

Application filed June 29, 1917. Serial No. 177,634.

To all whom it may concern:

Be it known that I, JOHN A. L. DETERS, a subject of the Emperor of Germany, residing at Chicago, in the county of Cook and State of Illinois, have invented certain new and useful Improvements in Automatic Cut-Outs for Gas-Burners, of which the following is a specification.

My invention relates to an automatic controller for gas jets and the like and has for its primary object the provision of improved means whereby the supply of gas may be automatically shut off from a burner when the flame is extinguished.

Other objects and advantages of my invention will become apparent from the following description taken in conjunction with the accompanying drawings, which form a part of this specification and illustrate the preferred embodiment of the invention.

In the drawings:

Figure 1 is a fragmentary top plan view of a gas stove embodying the features of my invention;

Fig. 2 is a section approximately on line 2—2 of Fig. 1;

Fig. 3 is a section on line 3—3 of Fig. 2;

Fig. 4 is a front elevation of an air plate forming part of my invention;

Fig. 5 is a reduced section taken approximately on line 5—5 of Fig. 1; and

Fig. 6 is a front elevation of a stop plate shown in vertical section in Fig. 5.

Reference numeral 10 indicates the top of a gas stove, which is supported in any suitable way not illustrated, and is formed with the arms 11 which define a grid for the support of cooking vessels. A burner 12 is supported beneath the grid 11 by means of an

offset bracket 13 at its rear extremity and a suitably shaped bracket 14 near its forward end. The burner is provided with the usual mixing chamber 15 which carries a depending lip 16 pierced for engagement with a

threaded rod 17. An air plate 18 is pierced at its lower end for engagement by the rod 17 and overlies the forward open end of the mixing chamber 15. Plate 18 may be flat but preferably is bowed outwardly, while the

forward end of the chamber 15 defines a substantial vertical plane. Air spaces 19 are thus provided at opposite sides of the plate 18 whereby a sufficient quantity of air is admitted into the chamber 15, where it mixes with gas entering the chamber through a jet

21. The plate 18 is apertured as at 22 to admit of the insertion of the jet 21 and to provide for admission of air, the aperture 22 being covered by a gate 23 which hangs on jet 21 and enlarges or reduces the air supply as the volume of gas increases or decreases. The aperture 22 admits into the mixing chamber the inner end of the jet 21 which is flared at both sides as at 24 in order to spread the gas injected into the chamber 15 and more thoroughly mix it with the air coming in from the sides of the forward end of the chamber and from aperture 22. It will be noted that while I maintain the vertical internal diameter of the jet 21 substantially the same from end to end, the horizontal diameter of the jet is greatly increased at its discharge end in chamber 15, thus providing a fan shaped jet of gas in the mixing chamber. The lip 16 and plate 18 are bolted together upon rod 17 by means of lock nuts 25 and the outer end of rod 17 is threaded into a tapped boss 26 on the gas supply pipe 27. A vertically extending tapped boss 28 is provided on the gas pipe 27. This boss is engaged by a pipe 29 which is outwardly threaded for substantially half its length and carries a nut 31 adapted to turn easily upon the threads. The lower end of pipe 29 communicates with the gas main 27, while the upper end is formed into a valve seat 32—pipe 29 being preferably formed of brass. A valve head 33 telescopes about the smooth upper end of pipe 29, the interior of the head 33 and pipe 29 being such that the action of gravity will permit movement of the head upon the pipe, and the head 33 is of sufficient weight to instantly overcome the pressure of gas in pipe 29. Mounted within the head is a needle valve 34 which, when elevated as shown in full lines in Fig. 2, permits gas to flow from main 27 through pipe 29 into jet 21. The valve 34 is preferably formed of a metal softer than the material of pipe 29, so that it will constantly fit the valve seat 32. The vertical elongation of aperture 22 is provided in order that jet 21 may be raised and lowered. The pipe 29 maintains the valve head 33 in substantially vertical position at all times, while the engagement between jet 21 and the sides of aperture 22 prevents rotation of the valve head upon the pipe 29. The lower end of the valve head normally rests upon the nut 31.

Traversing the burner at such a height above the same as to be subjected instantly to the heat of the flame is a bar 35 formed of aluminum, iron or any other substance 5 which has a high coefficient of linear expansion. The inner end of the rod is down bent as at 36 and fits in a vertical aperture provided in the bracket 13, thus anchoring the inner end of the rod against any horizontal 10 movement. The forward end of the rod terminates very close to the valve head 33 and is provided (see Figs. 2 and 3) with a rubber tip 37, the tip being held upon the rod preferably by means of a curled sheet 15 metal spring 38, which is compressed within the interior of the tip 37 and is slightly less in internal diameter than the external diameter of the rod 35. It will thus be seen that the spring 38 maintains the tip in fixed position 20 upon the end of rod 37 against any casual displacement while permitting a manual adjustment of the tip upon the rod. Normally, that is when there is no flame from burner 12, the cooled rod 35 is of such 25 a length as to cause tip 27 to stand out of contact with valve head 33.

In the operation of the above described device the nut 31 is threaded upwardly on pipe 29 to lift the valve head, causing a discharge 30 of gas from jet 21 and burner 35 is lighted, in the ordinary sense of the term, by the application of a match or any other flame. The burner flame immediately heats rod 35 and lengthens it until it contacts with the valve head 33, thereby jamming the valve head upon the smooth upper end of pipe 29 with sufficient force to prevent gravity induced fall of the head. The nut 31 is now threaded into the lower position indicated in dotted lines in Fig. 2. In this position of the parts the supply of gas to the burner and the flame from the burner are continuous inasmuch as valve 34, which is fixed to valve head 33, is held in elevated position by the 45 interposition of rod 35 between bracket 13 and valve head 33. Let it be assumed that a pot of water is heating upon the grid 11 and, in the absence of the housewife, boils over, putting out the gas flame from burner 50 12. The absence of the flame causes an instant cooling and consequent shortening of rod 35 which results in retraction of tip 37 from engagement by valve head 33 permitting drop of the valve head and the valve 55 32 and instant stoppage of supply of gas to the jet 21.

While I have described my invention as applied particularly to gas stoves it will be obvious that it has utility in connection with other devices, such, for instance, as illuminating gas jets and the like.

My improved valve lends itself readily to use as a gas stove lighter as will be seen by reference to Figs. 1, 5 and 6, wherein the 60 tip 39 is elongated a suitable distance and

provided with a reduced discharging end 41. In employing my valve as a lighter a stop plate 42, substantially in the shape of an inverted U, is employed, the legs 43 and 44 of which are spaced apart a distance sufficient to permit rotation of the valve head 33 within defined limits. In employing my improved valve as a lighter the nut 31 is set at such a height that a very small quantity of gas passes continually through the reduced discharging end 41 of the attenuated tip, 39, maintaining what is customarily termed a pilot light. As will be seen by dotted lines in Fig. 1, the stop plate 42 permits a considerable swing of the tip 39, sufficient to permit it to be aimed at one of the burners in the top of the stove. To ignite any one of the burners 12 the operator elevates the valve 34, valve head 33 and tip 39 manually from their position of rest upon nut 31 which increases the supply of gas to the tip 39, producing a long jet of flame. This long flame is directed at the burner which it is desired to light, and subsequently the tip 39 is returned to full line position, 85 shown in Fig. 1, and allowed to drop upon nut 31 which reduces the supply of gas to an amount just large enough to maintain the pilot light.

If the pilot light is not burning it may be 90 lighted by turning its end toward any lighted burner and raising it to produce a jet of gas long enough to reach the flame from the lighted burner.

While I have illustrated and described the 10 preferred embodiment of my invention it will be understood that one skilled in the art may make modifications thereof without departing from the spirit of the invention. I wish, therefore, not to be restricted to the 10 precise embodiment shown, except in so far as the same is limited in the appended claims.

I claim:

1. The combination with a gas burner and a source of gas supply therefor including an upright pipe, of a valve head slidably mounted upon said pipe, a gas jet carried by said head, the upper end of said pipe being formed with a seat, a valve carried by the head and adapted to close said seat when the head is in lower position, and a thermostatic rod anchored at the rear end of said burner traversing the flame area of the burner and terminating in proximity to said head.

2. The combination with a vertically disposed gas pipe provided with a valve seat in its upper end, of a valve head telescoping over said pipe and carrying an internal valve adapted to close said seat, there being a gas discharge duct communicating with the interior of said head at a point above the valve; a fixed gas burner fed from said head, and an expansible rod anchored at one end, 15

traversing the flame area of said burner, and having its opposite end positioned to contact with said valve head in the heated condition of the rod.

5 3. In a controller for gas valves the combination with an expansible rod, of a tip therefor comprising an apertured rubber

body, and a sheet metal spring slightly tensed within said aperture, the internal diameter of the coiled spring being slightly 10 less than the external diameter of said rod.

In testimony whereof I have affixed my signature.

JOHN A. L. DETERS.
